(57) **CLAIM**

I claim the ornamental design for a articulating mount, as shown and described.

DESCRIPTION

FIG. 1 is a perspective view showing a first position of the articulating mount showing my new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rear view thereof;

FIG. 8 is a perspective view showing a second position of the articulating mount of FIG. 1;

FIG. 9 is a front view of the articulating mount in FIG. 8; FIG. 10 is a right side view of the articulating mount in FIG. 8;

FIG. 11 is a left side view of the articulating mount in FIG. 8;

FIG. 12 is a top view of the articulating mount in FIG. 8; FIG. 13 is a bottom view of the articulating mount in FIG. 8; and

FIG. 14 is a rear view of the articulating mount in FIG. 8.

FIG. 15 is a perspective view showing a first position of another embodiment of the articulating mount showing my new design;

FIG. 16 is a front view of the articulating mount in FIG. 15; FIG. 17 is a right side view of the articulating mount in FIG. 15;

FIG. 18 is a left side view of the articulating mount in FIG. 15;

FIG. 19 is a top view of the articulating mount in FIG. 15; FIG. 20 is a bottom view of the articulating mount in FIG. 15; and

FIG. 21 is a rear view of the articulating mount in FIG. 15.

FIG. 22 is a perspective view showing a second position of the articulating mount of FIG. 15;

FIG. 23 is a front view of the articulating mount in FIG. 22; FIG. 24 is a right side view of the articulating mount in FIG. 22;

FIG. 25 is a left side view of the articulating mount in FIG. 22;

FIG. 26 is a top view of the articulating mount in FIG. 22; FIG. 27 is a bottom view of the articulating mount in FIG. 22; and,

FIG. 28 is a rear view of the articulating mount in FIG. 22. The broken lines shown are for illustrative purposes only and form no part of the claimed design.
